LUBRICATOR FOR JOURNAL BOXES

Jonas D. Bigelow, Yonkers, N. Y.

Application May 25, 1945, Serial No. 595,763

11 Claims. (Cl. 308—84)

1

This invention relates to improvements in lubricators for journal boxes, and particularly to improvements in pulsation shock and axle or box actuated journal lubricators designed and particularly adapted for use on railway cars and locomotive tenders to operate by the force resulting from combined road shocks and impacts due to unevenness in the track and road bed, change of train speed and relative movements or lost motions between rails, wheels, axles, journal boxes, journal wedges, journal bearings and pedestals.

The main object of the invention is to provide a positive means for automatically supplying lubricant to a storage reservoir located in or at the top of the journal box above the axle journal for the supply of the lubricant by gravity feed to the axle journal and coating bearing surfaces in controlled quantity.

Another object of the invention is to provide simple, reliable and effective motion actuated means which will operate the lubricator from pulsations of the journal box resulting from relative vertical movements between the journal box and journal due to irregularities of the road bed and rails.

Still another object of the invention is to provide means at the bottom of the journal box for forming an oil chamber or main oil reservoir and separating the same from the waste containing space thereabove, which means may serve as a support for a lubricating mechanism within the chamber and holding the waste from displacement.

Still another object of the invention is to provide a lubricating mechanism embodying a motion operated actuator and coating motion or power amplifying means for developing sufficient power, even under slight motions of the character described, for operating the lubricator.

With these and other objects in view, which will appear in the course of the subjoined description, the invention consists of the novel features of construction, combination and arrangement of parts, hereinafter fully described and claimed, and as illustrated in the accompanying drawings, in which:

Figure 1 is a vertical longitudinal section through a journal box embodying one form of the invention.

Figure 2 is a horizontal transverse section through the journal box on line 2—2 of Figure 1, showing certain parts broken away to better disclose certain features.

Figures 3, 4 and 5 are, respectively, a top plan view, a side elevation and an end elevation of and more particularly showing the supporting bracket, pump parts and actuator.

Referring now more particularly to the drawings, 1 designates a journal box of improved general type which receives the journal and shoul-

2

der portions 2 and 3 of the axle 4, and which, as shown herein, is of dust-excluding type, having at its rear a dust-guard well 5 enclosing the shoulder 3 and having at its front a door 6 for closing an opening or doorway in the upper portion of its front wall 7, the door and doorway surfaces being provided with sealing means to exclude dust, moisture and other foreign substances when the door is closed. This door structure coacts with the well to keep the interior of the box as free as possible from dust, rain or other moisture and other foreign substances causing friction and contamination of the lubricating oil, so that the interior of the box will be substantially free from such substances liable to cause friction or contaminate the oil or interfere with its flow to the bearing surfaces. The dust-guard well may be of the type shown in my Patent No. 2,177,606 of October 24, 1939, or my Patent No. 2,237,287, of April 8, 1941, and in my co-pending application, Serial Number 595,762, filed of even date herewith, and the door structure may be of the type particularly shown and described in said application. Of course, it will be understood that dust-guard wells and doors of other suitable types may be used, and that the present invention is not in any manner restricted to those shown. The upper portion of the journal box is suitably constructed to receive the usual journal bearings and wedges 8, which may be of any approved type. The box body may be generally of conventional form and construction except with regard to certain features hereinafter described.

Arranged within the bottom of the box above its bottom wall 9, and between the same and the axle journal, is a horizontally disposed partition plate 10, which is spaced from the bottom wall to form a main oil chamber or reservoir 11 and housing for the lubricator mechanism employed. This plate abuts at its rear edge against the rear wall of the box and is provided with a downwardly and forwardly inclined front flange 12 and downwardly and outwardly inclined side portions 13 formed with spaced flanges or lugs 14. These lugs fit within alcove-like pockets, or recesses 15 formed at the sides of the bottom of the box, certain of said lugs being apertured for passage of screws 16 engaging threaded sockets in the bottom walls of the recesses, whereby the partition plate is fastened in position. As shown, the flange 12 fits between the front walls of the front recesses at the sides of the box and closes the front of the chamber at that point. Between the plate 10 and the journal a waste-receiving space is provided and the plate portions 13 form retaining pockets or depressions 17 at the sides of the plate into which portions of the waste may seat, whereby the waste will be held from displacement in the rotation of the journal and in stable contact therewith.

The plate 10 also serves as a support for a bracket plate 18 detachably secured on the underside thereof by bolts, rivets or screws 19 and having a holding flange 20 depending therefrom. The lubricator, which is supported wholly or in part by this bracket plate, is located at the forward end of chamber 11 and comprises a cylinder 21 having an oil inlet member 22 for the feed of oil thereto from the chamber or reservoir 11, and having an outlet 23 with which connects one end of an oil feed tube 24.

The stem 25 of a piston working in the cylinder extends outward through a stuffing box 26, which projects through an opening in the flange 20, and is coupled to the forward end of a piston motion transmitting rod or bar 27 which extends rearwardly therefrom and is guided in a sub-bracket 28 secured to the bracket plate 18 or formed on the bottom of the journal box. On the rod or bar 27 is an abutment 29 and encircling the piston and rod between the stuffing box and abutment is a coiled spring 30 which is tensioned by movement of the piston on a working stroke in one direction to move it in the opposite direction or retract it. The bracket plate 18 is provided at its rear end with pairs of spaced ears 31 forming bearings for a transverse rock shaft 32 carrying a crank arm 33 which bears against the rear end of the bar or rod 27. To this shaft are fixed the forward ends of the arms 34' of a vertically swinging actuator 34 which is in the form of a weighted bar or plate fixed to the rear ends of the arms. This actuator is movable in a free space at the rear of the chamber so as to move in an arc of sufficient radius to effect, in connection with the spring 30, an efficient action of the pump with sufficient force to supply at all times an adequate amount of lubricant to the bearing surfaces of the box and journal.

The element 34 is normally held in the upward position shown in full lines in Fig. 4 by the pressure of the spring 30 against the abutment 29, which spring at the same time holds the piston in its rearward or retracted position. The element 34 is operated or swung vertically between its full line and dotted line positions shown in Fig. 4 whenever there is any relative vertical movement between the journal box and axle journal, by which the piston will be impelled on its working stroke to discharge lubricant through its outlet and into the tube 24. When this motion ceases and the pressure of the weighted operating element on the piston is relieved the piston will be retracted by the spring 30. As in the travel of a railway car or vehicle such movements between the journal box and journal occur more or less frequently the positive and automatic feed of an adequate amount of oil to the tube 24 for delivery to the bearing to keep them properly lubricated is ensured.

The oil supplied to the tube 24 is conducted by the tube through a delivery nozzle 24' to a storage reservoir or chamber 38 located at the top of the front of the journal box. This reservoir may be formed on or secured to the box and has a clean-out opening 39 normally closed by a plug 40. Secured to the bottom of this reservoir is a feed tube 41 having openings 42 for the controlled entrance of oil thereto, and the lower end of this tube communicates with a passage 43 opening into the top of the journal box and through a conducting surface 44, whereby the oil is caused to flow by gravity to the bearing surface. The upper end of the feed tube has connected thereto a vent tube 45.

An important advantage of the above-described construction of the journal box and lubricator is that the oil is positively and constantly supplied to the bearings by commotion, that all surfaces, including the journal shoulder which is difficult to lubricate, are kept lubricated, that the oil supplied is kept clean and free from dust, grit and other foreign substances, that the lubricator operates automatically without cost, and that the lubricator may be easily removed for cleaning, repairs or replacement, and may be supplied, installed and kept in working order at a comparatively low cost.

From the foregoing description, taken in connection with the drawings, the construction and mode of operation of my novel and improved impulse actuated lubricator for journal boxes will be readily understood without a further and extended description, and it will be seen that it provides a lubricator of simple, reliable and efficient type which will operate automatically to supply oil to the bearing surfaces under forces produced by relative vertical motions between the box and journal due to track or other road bed irregularities, thus ensuring the supply of oil at all times in adequate quantity to the bearing surface. The use of this automatic lubricator overcomes the inefficient or insufficient lubricating actions occurring when reliance is placed on the use of waste alone and without additional cost for operating purposes. While the construction disclosed is deemed preferable at the present time, it is to be understood that the invention is not limited thereto and that changes in the form, construction and arrangement of parts, other than those indicated, may be made within the scope of the appended claims, without departing from the spirit or sacrificing any of the advantages of the invention.

Having thus described my invention, what I claim as new and desire to secure by Letters Patent is:

1. In combination with a car axle journal box, and an axle journaled therein, means in the box for supplying oil from a source in the box to the bearing surfaces of the journal and journal bearing, said means comprising a pump cylinder, a piston operating in said cylinder, a pivotally mounted actuating device movable vertically under relative vertical working motions between the box and journal, and motion transmitting means between the pump piston and said device for operating said piston.

2. In combination with a car axle journal box, and an axle journaled therein, means for supplying oil from a source in the box to the bearing surfaces of the journal and journal bearing, said means comprising a pump cylinder, a piston operating therein, a spring retracted motion transmitting member coupled to the piston, a horizontal transverse rock shaft journaled in the box, a weighted actuating member connected to the shaft and movable vertically under relative vertical movements between the box and journal, and an arm carried by the shaft and engageable with the motion transmitting member to transmit working motion thereto.

3. In a lubricator for a car axle journal box and axle, said box having an oil reservoir chamber located beneath the journal, a pump cylinder mounted in the forward portion of said chamber, a spring retracted piston operating in the cylinder, and an actuating device disposed at the rear of the chamber and coupled to the piston and pivotally mounted to swing vertically under

70
75

relative vertical working motions between the box and journal to impel the piston on its working stroke.

4. In combination with a car axle journal box and axle, said box having an oil storage chamber, a pump cylinder located in said chamber and having an outlet for supplying oil to the surfaces to be lubricated, a piston operating in the cylinder, and a motion transmitting means for operating the piston including a spring retracted motion transmitting member located in the chamber and coupled to the piston, a horizontal transverse shaft at the rear of the chamber, a weighted actuating member connected to the shaft and movable vertically under relative vertical movements between the box and journal, and an arm carried by the shaft and engageable with the motion transmitting member to transmit working motion thereto.

5. In combination with a car axle journal, and an axle box having an oil reservoir chamber located beneath the journal, a pump cylinder disposed at the front of said chamber and having an outlet for supplying oil to the surfaces to be lubricated, a piston operating in said cylinder, a motion transmitting member connected with the piston and extending rearwardly therefrom in the chamber and movable forwardly to impel the piston on a working stroke, a spring for retracting the piston after each working stroke thereof, and an actuating device disposed in the rear portion of said chamber and pivotally mounted to swing vertically on a horizontal transverse axis under relative vertical motions below the box and journal for operating said member to impel the piston on its working stroke.

6. In combination with a car axle journal and journal box, a partition plate cooperating with the bottom of the box to form an oil reservoir, a pump cylinder supported by the plate at the forward portion of said reservoir and having an outlet leading forwardly therefrom for supplying oil to the surfaces to be lubricated, a piston operating in the cylinder, a reciprocating motion transmitting member connected at its forward end with the piston and in guided engagement at its rear end with the plate, said member being movable forwardly to impel the piston on its working stroke, a spring for retracting said member and piston after each working stroke thereof, and a pump actuating device at the rear of the chamber pivotally supported by said plates to swing vertically under relative vertical working motion between the box and journal for operating said member to impel the piston on its working stroke.

7. In combination with a car axle journal box, and an axle journaled therein, a partition plate supported in the box beneath the journal so as to form an oil reservoir chamber between the journal and the bottom of the box, a pump cylinder supported by said partition at the forward portion of said chamber and having an outlet leading therefrom toward the front of the box, a piston operating in said cylinder, a reciprocating motion transmitting member connected with the piston and extending rearwardly therefrom in said chamber, a spring for retracting the piston after each working motion thereof, and a pivoted actuating device supported by the partition at the rear of the chamber to swing on a horizontal transverse axis under relative vertical motions between the box and journal for operating said member to impel the piston on its working stroke.

8. In combination with a car axle journal box, and an axle journaled therein, a partition plate

supported in the box beneath the journal so as to form an oil storage chamber between the journal and the bottom of the box, a bracket plate supported from the partition plate within the chamber, a pump cylinder supported by the bracket plate at the front of said chamber and having an outlet leading therefrom toward the front of the box, a piston operating in the cylinder, a motion transmitting member in the chamber connected with the piston and extending rearwardly therefrom in guided engagement with the bracket plate, a spring for retracting the piston after each working operation thereof, a horizontal transverse rock shaft at the rear of the bracket plate having a crank arm engageable with the motion transmitting member to impel the piston on its working stroke, and a weighted pump actuating device pivotally connected to the shaft to swing vertically under relative vertical movements between the box and journal and operative on the shaft to move the motion transmitting device against the resistance of the spring to impel the piston on its working stroke.

9. In a lubricating mechanism for the bearing surfaces of a bearing box and journal, and in combination with the box and journal, a pump cylinder mounted horizontally in the box below the level of the journal, a reciprocating piston operating in the cylinder, and means including an actuating device pivotally mounted in the box below the level of the journal and coupled to the piston and controlled and operated by relative vertical movements between the box and journal for reciprocating said piston.

10. In a lubricating mechanism for the bearing surfaces of a bearing box and journal, and in combination with the box and journal, a pump cylinder mounted in the box, a piston operating in said cylinder, an actuating member mounted in the box to swing on a horizontal transverse axis under relative vertical movements between the box and journal, and a motion transmitting means between said member and the piston and cooperating with said member for transmitting reciprocating motion to the piston.

11. A pumping mechanism for application to a bearing box and journal for supplying oil to the bearing surfaces of the box and journal from a source of oil supply in the box including, in combination, a pump cylinder, a spring retracted piston operating therein, an actuating device pivotally mounted to swing vertically on a horizontal transverse axis under relative vertical movements between the box and journal, and means for transmitting motion from said device to the piston to impel the piston on its working stroke.
